BLOWER VALVE CONTROL ARRANGEMENT

Earl B. Lear, Detroit, Mich., assignor to Chicago Pneumatic Tool Company, New York, N. Y., a corporation of New Jersey

Application January 28, 1950, Serial No. 141,083

10 Claims. (Cl. 121—10)

1

This invention relates to rock drills of the pneumatic percussive type, and more particularly to an improved control for a blower valve arrangement for use when it is desired to blow cuttings and sludge from the bottom of a deep hole.

An object of the invention is the provision of an improved control arrangement whereby the blower valve can be automatically locked in blowing position and released therefrom by a simple manipulation and at a distance remote from the drill. The invention is especially suited for wagon drills which are so arranged that the blower valve is often out of reach of the operator.

A feature of the invention is a handle pivotally connected to the blower valve in such manner that the operator, by pulling a cable forwardly of the drill may turn the blower valve to blowing position wherein it is automatically locked, and by pulling the cable somewhat laterally of the drill, may release the blower valve for automatic restoration to drilling position. Another feature resides in the use of an adjustable torsion spring for resisting such forward movement, and a separate compression spring for resisting lateral movement.

Other objects and features of the invention will appear more clearly from the description to follow, when considered in connection with the accompanying drawings wherein:

Fig. 1 is a longitudinal section of a fragmentary portion of a rock drill embodying the invention, and showing the blower valve in blowing position;

Fig. 2 is a cross-section of a fragmentary portion of a rock drill showing the blower valve in drilling operation;

Fig. 3 is a plan view of the blower valve arrangement showing the handle in drilling position;

Fig. 4 is an end view of the blower valve arrangement as seen from line 4—4 in Fig. 5;

Fig. 5 is a cross-section view of the blower valve arrangement, looking rearward as seen from line 5—5 in Fig. 1;

Fig. 6 is a view of a return spring used in the blower valve arrangement;

Fig. 7 is an end view of the blower valve arrangement as seen from the right of Fig. 5;

Fig. 8 is a cross-section fragmentary view of the blower valve arrangement showing the handle in blowing position;

Fig. 9 is a cross-section view similar to that of Fig. 8, but showing the handle just after clearing a blowing position slot in a bushing used in the blower valve, but before being moved to drilling position;

2

Fig. 10 is a perspective view of a bushing used in the blower valve arrangement, and

Fig. 11 is a perspective view of the blower valve.

Referring now to the drawings and more particularly to Fig. 1, the rock drill comprises a cylinder 10 providing a piston chamber 11 in which a hammer piston 12 is caused to reciprocate. Integral with the lower portion of the cylinder 10 is a guide lug arrangement 13, which is slidably maintained in a shell (not shown) for the mounting of the drill. In a wagon drill assembly, which is not shown, but which is familiar to those skilled in the art, the shell is supported by a universal-type connection so that the drill can be operatively maintained in any vertical or horizontal position. A rotation mechanism for imparting step-by-step rotary movement to the piston 12 is arranged at the rearward end of the cylinder and comprises a rifle nut 14 threadably secured within the piston, a rifle bar 15 having a plurality of helical splines engaging the rifle nut, a head 16 on the rifle bar, a series of pawls 17 carried by the head, and a stationary ratchet ring 18 surrounding the head and pawls. The ratchet ring is supported by the cylinder 10 and by a back head 19 rigidly secured to the cylinder by draw bolt means (not shown).

Located in the rear end of the cylinder 10 is a counterbore 20 in which is arranged a valve chest 30 comprising a cylindrical valve cap 21 and a cylindrical valve block 22. The valve cap 21 is provided with a plurality of ports 23 for supplying motive fluid to the rear portion of piston chamber 11, while the valve block 22 has a pair of grooves 25 and 26 adjacently disposed about the inner periphery thereof, and a plurality of ports 27 extending inwardly from an annular groove 28 arranged on the rear face of the block. Ratchet ring 18 abuts against the rear end of valve block 22, and has a series of ports 29 which provide passage for the motive fluid from an annular groove 31 located on the enclosed face of the back head 19, said groove receiving the motive fluid by way of a passage 32 which is connected to a throttle valve 33 positioned within the back head. A key 34 is arranged to lock the valve block 22 and ring 18 against rotational movement.

Surrounding the rearward portion of the rifle bar 15 is a bushing 35 which is supported at its front end by the valve cap 21 and at its rear end by the valve block 22. A cylindrical distributing valve 36 is spaced from the bushing 35 and is slidably supported for reciprocal movement within the valve cap 21 and valve block 22, and has a flange 37 on its outer periphery. Supply passageways 38 and 39 formed in the wall of

cylinder 10, extend from groove 26 to the forward portion of the piston chamber 11. A groove 40, formed on the external surface of valve 36, connects groove 26 to the atmosphere by way of groove 25, a passageway 41 and port 42, to exhaust air from the chamber 11 in front of piston 12. A passageway 43, formed in the wall of cylinder 10, extends from the rear face of the distributing valve flange 37 to the portion of the piston chamber 11 defined in part by the rear face of piston 12. Another passageway 44 extends from the front face of distributing valve flange 37, through the valve block 22 and cylinder wall, to a blower valve arrangement 45. A relief port 46 is arranged to vent the rear face of distributing valve flange 37, while a cylinder exhaust groove 47 connects the piston chamber, in the region of midportion, to the blower valve arrangement 45. The exhaust groove 47 is located so that it is uncovered by the piston during both the forward and rearward stroke thereof. In accordance with conventional practice, a tube 48, for the conduction of live air to the drill hole, is positioned within the rock drill as shown. Alternatively a water tube may be used. The construction and operation of the distributing valve arrangement are essentially the same as in Craze Patent 2,443,894, June 22, 1948.

For the purpose of cleansing a deep hole which is clogged with detritus beyond the capacity of the air tube supply to remove it, a blower arrangement is provided which stops the drilling operation and diverts the full supply of live air through a hole in the drill steel. As best shown in Fig. 5, the present blower valve arrangement 45 comprises a valve bushing 49, a valve 50, a handle 51 attached to the valve, a retainer washer 52, and a return spring 53, all arranged as hereinafter described. The bushing 49 is press fitted to a bore 54 formed in a wall portion of the cylinder 10, transverse to the longitudinal axis of the cylinder. Two elongated slots 55 as well as two holes 78 (Fig. 2) are formed in the body of the bushing 49. One end of the bushing 49 is enlarged and contains at the outer end two circumferential slots 56 and 57, the former being of greater length but of less depth than the latter. At the other end of the bushing is a notch 58 for receiving and anchoring one end of spring 53.

The valve 49 has a pair of grooves 59 and 60, arranged on opposite sides of the body of the valve, the length of groove 59 being equal to that of slot 55, while groove 60 has a width corresponding to the diameter of holes 78. One end of the valve 50 is enlarged and contains a diametrical slot 61 for the reception of handle 51, which is pivotally maintained therein by a pin 62 extending transversely of the slot. A compression spring 63, arranged within a cavity at one end of the handle 51, abuts against the bottom of slot 61 and urges the handle about the axis of pin 62 toward an upright position in engagement with either slot 56 or 57 when the valve is positioned in the bushing 49. A bevel 64, on the lower inner surface of the handle 51, permits the handle to be cocked outwardly so that it may be swung out of engagement with slot 57, which is slightly greater in width than the thickness of the handle, and moved along slot 56. At the other end of the valve 50 a transverse pin 65 is positioned to maintain the washer 52 upon the valve. The washer 52 has a plurality of radially arranged rounded grooves 66 which seat the ends of pin 65 and a pair of diametrically opposite longitudinal holes 67, either of which holes

may be used to engage one end of spring 53. The washer 52 has a sliding fit on the valve 49 so that cocking thereof is prevented, while precompression of spring 53 urges the washer against the transverse pin 65 with sufficient force to prevent disengagement between the pin 65 and grooves 66. It is to be noted that the arrangement of the grooves 66 allows for the adjustment of the tension of spring 53 to compensate for friction and the weight of a pull rope or cable 68, which is connected to the handle 51. Such adjustment is accomplished by merely pushing the washer inwardly along the valve until the grooves 66 are clear of pin 65, and then rotating the washer to either increase or decrease spring tension as desired.

To change from drilling operation to blowing operation the cable 68 is pulled forwardly, or to the left in Fig. 1. After the initial torsion of spring 53 is overcome, the handle 51 is unseated from the Fig. 2 position and swung forwardly, thus increasing the wind up of the spring. As the handle is being moved, it rides along the shallow slot 56 in rubbing contact with the bottom thereof, due to the action of compression spring 63 on the handle. When the handle reaches the position in Fig. 1, and becomes aligned with the deeper slot 57, it drops therein, due to the action of compression spring 63. The operator may then release the pull on the cable and the handle will remain latched in full forward position. To release the handle, the cable is pulled sidewise, swinging the handle out of engagement with slot 57, whereupon the torsion spring 53 causes the handle to swing rearwardly to the Fig. 2 position. When the handle is in blowing position (Fig. 1), groove 59 of the valve 50 connects the cylinder exhaust groove 47 to passageway 44; when the handle is in drilling position (Fig. 2), groove 60 of the valve 50 connects passageway 44 to the atmosphere by way of an exhaust port 69, while groove 59 connects cylinder exhaust groove 47 to the atmosphere by way of exhaust port 71.

Referring to Fig. 1, the rock drill is shown in blowing position, in which position the distributing valve 36 is at rearward location, thus allowing work medium, such as live air, to pass from the throttle valve 33, through passage 32 and ports 29 in the ratchet ring 18, into groove 28, ports 27 and onward between the exterior of bushing 35 and interior of distributing valve 36, through ports 23 to the rear end of piston chamber 11, then about clearance space between the rifle bar 15 and rifle nut 14 and onward within the body of the hammer piston 12 to a hollow drill steel 72 (fragmentary portion only shown), and therethrough to the drill hole to blow away the detritus. At the same time live air passes from the piston chamber 11, through exhaust groove 47, groove 59 and passageway 44, to the front face of valve flange 37, to maintain the valve 36 in rearward position. It is to be noted that the air flowing from the piston chamber 11, through passageway 43, to the rear face of valve flange 37, is allowed to bleed to the atmosphere via exhaust ports 46 and 42.

When the rock drill is changed from blowing to drilling condition, exhaust groove 47 is connected to the atmosphere by way of groove 59 and exhaust port 71, while passageway 44 is connected to the atmosphere by way of groove 60 and exhaust port 69. In rotating from blowing position to drilling position, the valve 36 momentarily assumes a position in which the air pressure on the forward face of the valve flange

37 is cut off while the air pressure is continued on the rear face of the flange 37, by way of passageway 43, whereupon the valve 36 is shifted forward. With the valve 36 in forward position the front end of the valve is seated, thus cutting off flow of air to the rear of piston chamber 11, while the rear end of the valve uncovers the groove 26 allowing air to flow through supply passageways 38 and 39 to the piston chamber forward of the front piston face, to drive the piston 12 rearwardly in the piston chamber.

After the piston 12 has covered the main exhaust groove 47 and the passageway 43, and approaches the end of its rearward travel, the entrapped air in the piston chamber, to the rear of piston 12, is compressed and the resulting pressure, which acts on the front edge of the distributing valve 36, is of such degree as to cause the valve to be shifted rearward within the valve chest. Thereupon live air is admitted to the rear of chamber 11 and piston 12 is driven forward, as explained heretofore.

It is seen that the blower arrangement of the invention provides a means whereby the blower arrangement can be conveniently locked into blowing position and readily released therefrom, and may be operated at a distance remote from the rock drill, and particularly when the drill is mounted in a wagon drill assembly.

What is claimed is:

1. In a rock drill, a blower valve control arrangement comprising a bushing having a plurality of slots, a cylindrical valve member rotatably arranged within the bushing and having a pair of grooves disposed in opposition on the periphery thereof, handle means pivotally affixed to the valve member and engageable with end slot means on the bushing to positionally maintain the valve in either of two positions, one of which aligns the bushing slots and the valve grooves whereby the drill is conditioned for blowing operation, the other of which aligns the bushing slots and valve grooves whereby the drill is conditioned for drilling operation, and adjustable resilient means one part of which is affixed to the bushing another part of which engages the valve member to provide for moving said valve member from blowing position to drilling position upon manipulation of the handle means.

2. In a rock drill, a blower valve arrangement according to claim 1 in which the adjustable resilient means comprises a coil spring which surrounds an end of the valve member, a retainer washer, and a transverse pin affixed to the valve and having protruding end portions which engage grooves on the face of the washer.

3. In a rock drill, a blower valve arrangement according to claim 2 in which the end slot means on the bushing comprises a first slot and a second slot, the first slot being of greater circumferential length but of less depth than the second slot, said handle being adapted for sliding contact with either the first or second slot and having resilient means arranged to urge the handle toward sliding contact with the end slot means.

4. In a rock drill, a blower valve arrangement according to claim 3 in which a shoulder is formed between the first and second slot to maintain the handle in the second slot under the influence of the resilient means operating on the handle.

5. In a rock drill, a bushing, a blower valve

70

supported in said bushing for rotation between two extreme positions of stable equilibrium including a normal position and an operated position, a torsion spring interposed between the bushing and valve and constantly urging the latter toward its normal position, a handle connected to the valve to rotate therewith as a unit to turn the valve to operated position, locking means automatically operable upon attainment of the operated position to lock the valve against the force of the spring, said handle being mounted for independent movement for releasing the locking means to permit the spring to return the valve to normal position.

15 6. In a rock drill, a bushing, a blower valve supported in said bushing for rotation between two extreme positions of stable equilibrium including a normal position and an operated position, a torsion spring interposed between the bushing and valve and constantly urging the valve towards its normal position, said blower valve having a radial slot, a handle mounted in said slot to turn the valve against the force of the spring upon being actuated tangentially, said handle being pivoted in the slot to permit the handle to move independently of the valve when actuated laterally, resilient means opposing such independent movement, automatic means including said resilient means for locking the valve in operated position, means for releasing the locking means to permit the torsion spring to restore the valve to normal position, and remote control means for pulling the handle whereby the operator may control the position of the blower valve by pulling the handle either tangentially or laterally.

20 7. In a pneumatically powered drill having a blower valve arrangement for blowing detritus from a hole being drilled, and including a valve member rotatably positionable for delivery of full line pressure for blowing operations, a control arrangement for the valve member comprising, a lever means pivotally affixed to the valve member and adapted to engage a slot means whereby the valve member is maintained in blowing position, and resilient means disposed between the body of the drill and said valve member and adapted to constantly urge the valve member away from blowing position.

25 8. In a pneumatically powered drill having a blower valve arrangement according to claim 7, and adjustable means for regulating the tension of the resilient means.

30 9. In a pneumatically powered drill having a blower valve arrangement according to claim 8, a resilient means for maintaining the lever means in engagement with the slot means.

35 10. In a pneumatically powered drill having a blower valve arrangement according to claim 9, a remote control means for moving the lever means for placing the valve member in blowing position.
